Incorporated, New York, N. Y., a corporation of New York

Application January 31, 1956, Serial No. 39,986

Term of patent 7 years

(Cl. D82—2)

Fig. 1.

Fig. 2.

Fig. 3.

Fig. 1 is a front elevational view of a confection showing my new design, the back thereof being conventionally plain and unornamented;

Fig. 2 is a side elevational view of the confection shown in Fig. 1; and

Fig. 3 is a bottom end view thereof.

The essential features of my design reside in the portions shown in solid lines on the drawing.

I claim:

The ornamental design for a confection or the like, substantially as shown and described.
